UNITED STATES PATENT OFFICE

LOUIS H. MORIN, OF NEW YORK, N. Y., ASSIGNOR TO DOEHLER DIE-CASTING COMPANY,
A CORPORATION OF NEW YORK

CHAIR

Application filed February 9, 1927. Serial No. 166,836.

My invention has particular reference to articles of furniture which are intended to be sat upon, such as chairs or the like, although in certain respects my invention is applicable 5 to other types of furniture. My invention is particularly advantageous as embodied in metal seats and since it is well illustrated in a metal chair, I shall use that embodiment as the illustration with which to explain my 10 invention.

Furniture is by its nature, as a rule, of considerable bulk in proportion to its weight and it therefore occupies a considerable amount of space when packed for shipment in the 15 erected condition. The trend has therefore been towards the construction of demountable, or knock-down, furniture, that is, furniture which may be dismantled without injury to the finish or fit of parts so that the various 20 parts may be packed in much smaller compass, and upon receipt by the user may be assembled into a complete substantial article.

To an increasing extent metal is replacing wood as the material from which furniture 25 is made, and the problems which arise in devising demountable or knock-down furniture are best solved in metal. The greater strength of metal permits the construction of parts which are of relatively small size and 30 may be of graceful proportions without the sacrifice of a maximum of strength and firmness. It is desirable also that the parts of the furniture be suitable to packing in flat containers, and metal parts are especially 35 adapted for this purpose.

My invention utilizes these properties in a particularly advantageous way. By it, I provide suitable parts for the desired piece of furniture, such as a chair, and means at the 40 joints between the various parts, such as between the legs and the seat, as well as between the back and the seat, whereby the various members are firmly attached in the cooperating relation and are especially 45 adapted to support the strain which is applied to the joints during the course of usage. Another feature of my invention is the fact that the parts are very light, substantially 50 as light as the corresponding parts of wooden furniture of the same type. This lightness

I obtain by the use of parts of hollow section, formed from such materials as tubes or angle members.

In a preferred embodiment of my invention, I provide a member which may desirably be formed of metal tubing bent into an inverted U shape, which is adapted to form the rear legs and the back member of a chair. This may be called the main member. Another member consists of a rectangular piece, 55 desirably formed of metal angle-bar section, which is adapted to serve as the seat frame of a chair, which has bracket members adapted to engagement with the tubular back member, and has leg sockets at the front. Two 60 front leg members are also provided, which are desirably hollow and which are equipped with plug portions at the upper ends adapted to engagement with the sockets on the seat member. The respective parts are desirably 65 held in proper relationship by means of bolts or screws. Additional strength may desirably be provided in the back member portion by the inclusion of solid inserts or filler members within the tubular portions, at points of 70 maximum stress, which are adapted to engage with the bolts which attach the seat member to the back member. The socket attachment of the front leg members 75 preferably provides a wedge fit which will retain 80 the front legs against ordinary usage, but additional supporting means, consisting of suitable screws, are desirably provided for more substantial fastening. A filler member 85 such as a cushion, or a cane back, is desirably 90 provided, cooperating with the main back member. This may consist of a subframe to which a cushion or a woven cane panel, or other support is attached, which may be inserted within the back frame by springing 95 the ends of it apart, inserting the subframe, and cushion or caning, and releasing the ends. The natural elasticity thereof provides substantial pressure against the subframe and it is accordingly held firmly in place. Additional pressure may conveniently be provided by the insertion of the bolts holding the seat member to the back member. A very stout 100 piece of furniture is thus provided which is light in weight, of graceful proportions, and

which is demountable into relatively small, flat parts suitable for convenient packing for shipment, and is readily reassembled by the user.

5 Other features and advantages of my invention will appear from the following description. I shall now describe the illustrated embodiment of my invention and shall thereafter point out my invention in claims.

10 Fig. 1 is a front view of the assembled metal parts comprising a preferred embodiment of my invention in a chair;

Fig. 2 is a side view of the same embodiment;

15 Fig. 3 is a perspective view of portions of the seat frame member and back member of my invention showing the method of attachment;

Fig. 4 is a perspective view of a front leg member of the same embodiment, and

20 Fig. 5 is a bottom view of a seat frame member.

The illustrated chair is made of metal, the several sections being respectively of cast metal and of drawn metal. There are desirably six sections as shown, these being a back member, seat frame, front legs, seat cushion and back cushion. The back member 1 may desirably be made of drawn metal tubing, 25 which in the embodiment illustrated, is of rectangular section with one side grooved. Alternatively the back member may be formed of other material by other convenient processes. In the embodiment shown, the 30 back member has the shape of an inverted U with a substantial curvature in the plane of the sides as indicated in Fig. 2. The grooved side of the tube faces between the sides of the member. A seat frame member 35 2 is provided which is desirably formed as a rectangle with flat top and sides. It is desirably made of cast metal, such as a die-casting, in an angle bar section as indicated in Fig. 3. The seat member is provided with 40 bracket members 3 at the rear corners which are adapted to cooperate with the back member 1, and with socket members 4 at the front corners. These sockets as shown are desirably of triangular shape with curved corners 45 and are desirably tapered from top to bottom. The bracket members 3 are provided with 50 holes 5 as indicated, through which bolts 6 enter.

The bolts 6 are adapted to cooperate with 55 filler members 7 which are inserted within the tubular back member 1. These filler members 7 have the form of the interior of the drawn tubing and desirably make a fairly snug fit therein. They are drilled and tapped 60 to cooperate with the bolt 6 and provide sufficient strength of metal to allow of a substantial clamping effect by the bolts. They also provide additional strength in the back member at the point of maximum stress, where 65 the seat member is attached.

Front leg members 8 as shown in Fig. 4 are provided. These members are desirably although not necessarily of cast metal such as die-castings and are desirably made in a hollow form with plug members 9 at the upper ends, adapted to cooperate with the sockets 4 upon the front corners of the seat member. The plug members 9 are provided with bolt holes 11 and the seat member 2 is provided with tapped bolt holes 12. Bolts 14 are 70 provided cooperating with the holes 11 and 12 for securing the leg members 8 in place.

A back cushion member 15 is provided which may desirably consist of a subframe 16 within which is positioned a filler 17 which may be of woven cane as in the illustrated embodiment or may be a fabric cushion, such as velvet, or cretonne, or other desirable material.

80 Alternatively, the filler 17 may be formed of a sheet of metal, which may, if desired, be suitably embossed or perforated. It may, if desired, be embossed with any one of a variety of artistic designs, or may be embossed and perforated in imitation of woven cane. Similarly a seat cushion member 18 is provided and positioned upon the seat frame 2 in any convenient way. This cushion may be formed of material in a suitable match with the material forming the back cushion member 17, 90 such as velvet, cretonne, woven cane, etc. Or, alternatively, if it is not necessary that the seat cushion be soft, as may be the case if the chair is used for auditorium purposes or for dining room purposes, the seat as well may be 95 formed of a sheet of embossed or perforated metal.

100 The seat cushion may be formed and attached by any one of a number of convenient methods. It may conveniently consist of a base member 19 which may desirably be a piece of thin wood, such as ply wood, or other suitable material, or may if desired be sheet metal. Upon the foundation member 19 may be placed a cushion filler 20 which may consist of any suitable padding material, such as 105 curled hair, excelsior, or suitable springs. The cushion cover 21 may, as previously described, consist of suitable fabric to match the back cushion member 17. It is of course 110 obvious that if a padded cushion is constructed, the previously suggested sheet metal seat is inapplicable, except in the event that it forms the foundation member. The cushion may desirably be attached by screws 22 115 through the seat frame member 2 as indicated.

120 It is to be noted that provision is made in the construction of the chair for unusual strength. The back member 1 consists of a tubular structure of maximum lightness 125 and strength, which is reinforced at the point of maximum stress. It provides a very strong foundation member for the chair construction which is extremely resistant to deformation of any sort. The seat frame member 130

is also a unitary part, formed of material having a section adapted to the production of maximum strength and lightness. The seat member is attached by large and stout 5 bolts to the reinforced point of the back member. Additional strength is provided in the seat member by the brackets 3 which are of sufficient length to minimize the effect of leverage at the point of attachment. The front 10 members likewise are of a shape providing the maximum strength and lightness, and are very firmly attached.

My device has been described as in the assembled state. It is readily disassembled, by 15 the removal of the six screws. The removal of the screws 14 permits the removal of the front leg members. These legs are held in place to a certain extent by a wedging action within the sockets 4. They are, however, 20 readily removed therefrom by suitable twisting and pulling movement. The seat member 2 is then detachable from the main back member 1 by the removal of the bolts 6. The inner members 7 remain in place by virtue 25 of a rather snug fit in the tubular member 1. For shipping, the seat member 2 may be packed within the curve of the back member 1, and the front legs may be stowed between the back legs. In this way a flat, compact 30 package is formed of a chair which is adaptable to enclosure in a flat packing case and to shipment in a minimum space. Assembly 35 of the chair is conveniently performed by similar operations in reverse sequence to those for demounting, the seat member being bolted in place by insertion of the bolt 6, and the front leg members attached by insertion of the bolts 14, whereafter the chair is ready 40 for use as a complete piece of furniture.

By the device of my invention I have thus 45 provided a piece of furniture which is adapted to be formed of metal parts, which is readily demountable into substantially flat members, and readily packed for shipment in a small space, which is of exceptional strength, 50 ruggedness and rigidity, and which is of light graceful lines.

It is obvious that other modifications may be made in the construction shown in the 55 drawings and above particularly described without departing from the principle and scope of my invention.

I claim as my invention:

1. A chair or the like comprising a tubular main member having a grooved side, an 55 additional member attached thereto, and reinforcing means at said point of attachment comprising a solid strengthening means recessed for said groove and positioned within 60 said tubular member at said point of attachment, and attaching means comprising a perforation in said additional member, a threaded perforation in said strengthening means and a clamping bolt inserted therein.

65 2. A knock down chair comprising a U

shaped tubular back piece having a groove extending along the interior of the U, a panel adapted to fit closely within said groove, vertically elongated fillers within the tube and contacting with the front and rear walls 70 thereof, a seat frame having vertically elongated bearing surfaces for engaging the back piece and threaded means passing through the same and engaging said fillers.

In witness whereof, I hereunto subscribe 75 my signature.

LOUIS H. MORIN.
